UNITED STATES PATENT OFFICE

146,703

DESIGN FOR AN ASH TRAY

George H. Decker, Beaumont, Calif.

Application April 26, 1946, Serial No. 129,001

Term of patent 14 years

(Cl. D85—2)

To all whom it may concern:

Be it known that I, George H. Decker, a citizen of the United States of America, residing at Beaumont, county of Riverside, and State of California, have invented a new, original, and ornamental Design for an Ash Tray, of which the following is a specification, reference being had to the accompanying drawing, forming a part thereof, wherein:

Figure 1 is a top plan view of an ash tray showing my new design;

Figure 2 is a side view;

Figure 3 is a sectional view on line 3—3 of Figure 1;

Figure 4 is a bottom plan view.

I claim:

The ornamental design for an ash tray, as shown.

GEORGE H. DECKER.
